UNITED STATES PATENT OFFICE.

THADDEUS CAHILL, OF NEW YORK, N. Y.

TYPE-WRITING MACHINE.

1,097,789.

Specification of Letters Patent.

Patented May 26, 1914.

Application filed October 17, 1900, Serial No. 33,365. Renewed December 4, 1905. Serial No. 290,174.

To all whom it may concern:

Be it known that I, THADDEUS CAHILL, a citizen of the United States and of the city, county, and State of New York, temporarily residing at Washington, in the District of Columbia, have invented certain new and useful Improvements in Type-Writing Machines and other Similar Instruments, of which the following is a specification.

My invention has for its object to avoid the possibility of the operator printing letters one on top of another at the end of a line, and consists in the parts, improvements and combinations hereinafter described and claimed.

For convenience I shall call my invention an automatic printing-preventing device. This automatic printing-preventing device I shall show as applied to a type-writing machine of the general type illustrated in my pending application No. 735,813, filed November 4th, 1899; but when the invention as applied to one type of machine has been made clear, mechanics skilled in the art will be able easily to apply it to other types of machines.

In the accompanying drawings Figure 1 is a sectional view through a type-writing machine to which my invention is applied; Fig. 2 is a rear elevation; Fig. 3 is a plan view, partly in section, on the line 3, 3, of Fig. 1; Fig. 4 is a detail top view; Fig. 5 is a detail perspective.

Similar reference numerals refer to similar parts in all the figures.

1 is the bed-plate; 2, the top-plate; 3, 3, side-standards which are screwed to the bed-plate and which rise from it to support the top-plate and other parts of the mechanism; and 4 is the fulcrum-plate.

5 is the platen; 6, the platen-carrying frame; 7, the yoke; 8, the rod connecting the platen-carrying frame with the yoke; and 9, the back-rod on which the yoke runs.

10 is a type-bar set in the hanger 11 and connected by the pull-down rod or wire 12 with the lever 13, which is centered at 14 and has pivoted to its other end the movement-receiving arm 15, which is controlled

by the key to take movement from the motor-frame 16, hereinafter described, for the actuating of the type-bar. The movement-receiving arm 15 lies normally clear of the motor-frame 16, so that said frame can play

without giving movement to said arm. But

when the key 17 corresponding with the movement-receiving arm 15 is depressed, it throws said movement-receiving arm over said frame and at the same time closes the circuit of the magnet which operates said frame, so that said magnet actuates said frame and the type-bar. To this end the key 17 (which is fulcrumed at 18 and held in its normal position by a spring 19) acts, when depressed, through the key-extension 20, upon the latch 21, pivoted to the horizontal arm of the bell-crank 22; and thus through said latch, bell-crank and the link 23 throws the movement-receiving arm 15 over the motor-frame 16. The spring 24 serves to hold the latch 21 normally in engagement with the key-extension 20. The bell-cranks 22, 22, are set in slots milled in the hanger-bar 25, upon the rod 26. At the same time that the key thus throws the movement-receiving arm 15 over the motor-frame 16, it gives movement to the circuit-closing frame 27, which in turn gives movement to the contact-spring 28, bringing said spring into contact with the contact screw 29, thereby closing the circuit of the magnet 30, whose armature 31 is connected by the rod 32 (whose screw-threaded shank enters the armature and is provided with facility for adjustment in the lock-nut 33) with one of the arms of the motor-frame 16. Said magnet, becoming energized, gives movement to the frame 16, and thus through the movement-receiving arm 15, lever 13, and pull-down wire 12, to the type-bar 10, throwing the type up toward the printing point so that it prints. At the same time the magnet 30 gives movement through the motor-frame 16 to the link 34 (which is connected at 35 with the motor-frame and at 36 with the releasing-frame) to the releasing-frame 37, which is centered at 38 and serves both to release the latch or jack 21, thereby permitting the circuit-closing frame 27 to return to its normal position in advance of the release of the key. The circuit-closing frame 27, returning to its normal position, breaks the circuit of the magnet 30, which thereupon loses its magnetism, and so permits the motor-frame 16 to return to its normal position under the influence of its contractile returning spring 39. At the same time the bell-crank 22, the latch 21 and the movement-receiving arm 15, connected with the bell-crank by the link 23, return

to their normal positions under the influence of gravity and the returning spring 40. The type-bar at the same time, continues its excursion toward the printing point until the 5 type strikes, when the type-bar rebounds and returns to its normal position under the influence of the rebound, gravity and the returning spring 41.

Inserted in the circuit of the magnet 30, 10 along with the battery 42, rheostat 43 and switch 44, is a contact-spring 45 and contact-screw 46, the latter being set in the lug 47 of the bed-plate, but insulated therefrom. When the circuit is closed by the depressing 15 of a key, the path of the current, we may assume, is from the battery 42 to the handle of the rheostat 43, thence through the rheostat to the switch 44, thence by the wire 71 to the insulated arm 72 which carries the 20 contact-screw 29, before described, thence to the contact-spring 28, thence (when the key is depressed) to the other contact-spring 45, thence to the contact-screw 46 and from the 25 contact-screw 46 to the magnet 30, and through said magnet back to the negative pole of the battery. The contact-spring 45 and the contact-screw 46 form a part of the printing-preventing mechanism as the same is illustrated in the accompanying drawings, 30 though my invention may, as will appear hereinafter, be carried out without such a contact device.

Traveling with the carriage is a trip piece 48, which is centered at 49 on the rack-frame 35 and held by an expansive spring 50 normally resting against the under side of the head of the screw 51. Just back of the rack-frame is another rack 52, which is mounted by means of the bridle-lever 53 (centered at 40 54) and the arm 55 of the rock-shaft 56, whose other arm 57 carries a screw 58, adjustable by means of the lock-nut 59, which screw carries a piece of hard fiber, vulcanite, or other suitable insulating material, 60, 45 which serves, when actuated by the trip 48 in the manner hereinafter described, to act upon the spring 45 to move the same from its normal position of contact with the contact-screw 46, thereby opening a gap in the 50 circuit of the magnet 30, so that printing is rendered impossible.

Traveling on the rack 52 is a little casting or carriage 62, which is furnished with a pawl, 63, centered at 64, and held by a tiny expansive spring 65 normally in engagement with the rack 52. There is also attached to the casting or carriage 62 a little fly, 68, which is centered at 66 and held by a tiny contractile spring 67 in the normal position shown in the drawings. The pawl 63 serves to hold the carriage in whatever position upon the rack 52 it may be placed, but the operator, by catching the fly 68 and the vertical arm of the pawl 63 between the 60 finger and thumb, can move the carriage 62

to any position desired, so as to cause the printing-preventing action to take place at any part of the line desired. To assist the operator in this, the rack 52 is graduated and marked to indicate in any given position of the casting 62, the point in the travel of the carriage at which printing will be prevented. The trip 48 serves as the carriage moves down the line to encounter the fly 68, thereby throwing the rack 52 in the direction of the arrow, (Figs. 2 and 4) giving movement to the arm 57 of the rock-shaft, which in turn acts upon the spring 45, breaking the circuit of the magnet 30, so that however much the keys may be operated 70 said magnet cannot act, and no type-bar can print. If, after the printing has been thus prevented, the operator wishes to write other letters, he touches the trip 48, pressing down the forward end, thereby raising the 75 rear end above the fly 68, whereupon the spring 70 attached to the arm 57 of the rock-shaft 56 restores the parts to their normal positions, thereby permitting the spring 45 to again come in contact with the screw 46, 80 thus closing the gap in the circuit so that the operator can now continue his printing. When the carriage reaches its extreme downward or left-most position the lug 69 on the 85 rack-frame comes in contact with the piece 90 48, attached to the rack 52. The rack 52, as before said, is graduated so that the point at which the dog 63 engages the rack 52 corresponds with the number on the front scale 95 at which the printing will be prevented. 100

It will be observed that my printing-preventing device operates upon a broadly new principle; to wit: by preventing a magnet or other motor device from acting to give movement to the type-bar. The typebars 105 thus are not locked—each type-bar is free to move—but the motor is prevented, as I have said, from actuating them.

The device illustrated in the drawings is a convenient means of carrying out my invention, but it is only one of several that I have invented, and many modifications may be made without departing from the spirit of my invention or from certain essential combinations and sub-combinations set forth 115 in the statement of claim at the end hereof. Thus, for example, it will be obvious that the means intermediate the carriage and the circuit breaking device may be widely varied without departing from certain essential 120 features of my invention. Instead of using the circuit-controlling device operated by the travel of the paper-carriage to prevent the magnet 30, or its equivalent, from acting, by opening a gap in the working circuit, as illustrated in the drawings, the same effect may be produced by using said circuit-controlling device to close a circuit of small 125 resistance which is arranged to serve as a shunt to the working circuit, and which, be- 130

ing of so much less resistance, draws off so much of the current that the magnet fails to operate. Or I may dispense entirely with the circuit terminals (the contact-spring 45 and contact screw 46 or their equivalents) by arranging the arm 57 or any equivalent part to block the movement of the circuit-closing frame 27, as, for instance, by swinging said arm 57 over one of the horizontal arms 5 of said frame so as to prevent it from lifting when acted on by the key, and in this case it would be convenient to put a pawl or fly on the end of the arm 57, to swing over the circuit-closing frame 27. The position 10 of the rock shaft 56 with its arms 55 and 57 may obviously be inverted, the shaft being made vertical and the arms to lie horizontal if desired, the lengths of the arms also being altered as required. Also, the independently 15 mounted rack 52 might be dispensed with, and the casting 62 or its equivalent made to travel upon the rack-frame to engage a fly on the arm 55 or its equivalent. Numerous other modifications may be made 20 without departing from certain essential features of my invention.

By the normal movement of the paper carriage, I mean that movement which the carriage executes step by step, as the printing of the successive letters of a word progresses. In printing English words, the normal movement of the carriage is usually if not always toward the left, as viewed 25 from the position of the operator in front of the machine; while in printing Hebrew characters the normal movement would be toward the right.

Having illustrated my invention as applied to the kind of type-writing machine 30 figured in the drawings, it will be obvious that it may be applied to any other sort of typewriting machine whatever in which the type-bars are actuated by electricity. For in any such device the operating of the 35 magnet or magnets can be prevented in one of the ways above described. Also, my invention is applicable to other forms of motor device. It has been pointed out by me in diverse pending applications and prior 40 patents that some other form of motor device than an electro-magnet may be used to actuate the type-bar-impelling motor-frame shown in the drawings, of any equivalent 45 thereof. Thus, for example, I have pointed 50 out how a pneumatic device might be used instead. In such a case the arm 57 might be made to operate a valve, which would shut off the air or other fluid from the motor device instead of operating, as in the drawings, a contact device which shuts off the 55 current; or the arm 57 might be used to block the frame 27 or its equivalent, which is illustrated in the drawings as controlling a circuit, but which it has been pointed out 60 in previous patents and pending applica-

tions of mine, might be used instead to operate a valve. Also, said arm 57 or its equivalent might be arranged to prevent the printing by controlling the motor in some other manner than by cutting off the 70 power or rendering the admission of power to the motor impossible. Thus, for example, said arm 57 or its equivalent might be made to swing, when operated by the carriage, over the motor-frame 16 or its equivalent, or into the path of movement of the armature 31, or other motor device, so as to prevent the motor from moving a sufficient distance to effect printing. But, while this 75 is one possible mode of carrying out my invention, I consider that mechanism operating upon the principle of that illustrated in the drawings, to wit: by cutting off power from the motor—to be preferable to the other manner above pointed out, which consists in blocking the movement of the motor-frame, armature, or other motor device. But I wish protection for the one as well 80 as for the other.

Various features of construction are illustrated in the drawings and described in the specification, in order to make clear my present invention which, however, do not form a part of this application, but form parts of the subject matter of prior pending applications 90 of mine, Nos. 735,813, filed Nov. 4, 1899, which relates to the mechanism for impelling and releasing the type-bars, regulating the strength of the printing blow and various other matters, and No. 30,163 which 95 relates to the ribbon operating mechanism, etc. I wish it to be understood that I do not claim in this specification anything that is claimed in my prior pending applications before mentioned, Nos. 735,813 and 30,163. 100

It will be understood, then, that my invention, as it is capable of many variations, is not limited to the details figured in the drawings hereinbefore described, but that

What I claim as of my own invention and desire to secure by Letters Patent upon this application is—

1. In combination, in a typewriting machine (a) a traveling paper carriage; (b) an electrical motor and (c) means operated by the normal movement of said paper carriage and acting to prevent said motor from operating.

2. In combination, in a typewriting machine (a) a traveling paper carriage; (b) a power device; (c) a source wherefrom power is supplied to said power device, and (d) means operating to prevent the supply of power from said source to said power device; the means last mentioned being operated by the normal movement of the paper carriage aforesaid.

3. In combination, in a typewriting machine (a) a traveling paper carriage; (b) an electromagnet; and (c) means operated

by the normal movement of the paper carriage aforesaid and acting to prevent said magnet from operating.

4. In combination, in a typewriting machine (a) a traveling paper carriage; (b) an electromagnet; and (c) circuit-controlling means for said electromagnet, operated by the normal movement of said paper carriage and acting to prevent said magnet from operating.

5. In combination, in a typewriting machine (a) a traveling paper carriage; (b) an electromagnet; (c) a contact device in the circuit of said electromagnet normally closing a gap in said circuit; the paper carriage aforesaid controlling said contact device and acting by its normal movement to open a gap in the circuit of the magnet aforesaid, thereby to prevent said magnet from operating.

6. In combination, in a typewriting machine (a) a traveling paper carriage; (b) a motor; (c) means operated by the normal movement of said paper carriage and acting to prevent said motor from operating; and (e) means whereby the point in the normal travel of said paper carriage at which it acts to prevent the motor aforesaid from operating is regulated.

30 7. In combination, in a typewriting machine (a) a traveling paper carriage; (b) a power device; (c) a source wherefrom power is supplied to said power device; (d) means operating to prevent the supply of power to said power device; the means last mentioned being operated by the normal movement of said paper carriage; and (e) means whereby the point in the normal travel of the paper carriage at which it acts to prevent the motor aforesaid from operating is regulated.

40 8. In combination, in a typewriting machine (a) a traveling paper carriage; (b) an electromagnet; (c) means operated by the normal movement of said paper carriage acting to prevent said magnet from operating; and (d) means whereby the point in the normal travel of the paper carriage at which it prevents said magnet from operating is regulated.

50 9. In combination, in a typewriting machine (a) a traveling paper carriage; (b) an electromagnet; (c) circuit controlling means for said electromagnet operated by the normal movement of said paper carriage, and serving when thus operated to open a gap in the circuit of said electromagnet; and (d) means whereby the point in the normal travel of the paper carriage at which it operates the circuit controlling means aforesaid is regulated.

60 10. In combination, in a typewriting machine (a) a traveling paper carriage; (b) an electromagnet; (c) a contact device in the circuit of said electromagnet normally closing a gap in said circuit; the paper car-

riage aforesaid controlling said contact device and acting by its normal movement to open a gap in the circuit of the electromagnet aforesaid, thereby to prevent said magnet from operating; and (d) means whereby the point in the normal travel of the paper carriage, at which it opens the gap at the circuit of the magnet aforesaid is regulated.

70 11. In combination in a type-writing machine, (a) a traveling paper carriage; (b) a motor; (c) one or more keys at the key-board acting when depressed to bring said motor into operation; and (d) means operated by said paper-carriage and acting to prevent said motor from operating.

80 12. In combination in a type-writing machine, (a) a traveling paper-carriage; (b) a motor; (c) one or more keys at the key-board acting when depressed to bring said motor into operation; (d) means operated by said paper-carriage and acting to prevent said motor from operating; and (e) means whereby the point in the travel of the paper-carriage at which it acts to prevent the motor aforesaid from operating, is regulated.

85 13. In combination in a type-writing machine (a) a traveling paper-carriage; (b) a motor; (c) one or more keys at the key-board acting when depressed to bring said motor into operation; (d) means for printing operated by said motor; and (e) means operated by the carriage aforesaid, acting to prevent said motor from printing.

90 14. In combination in a type-writing machine, (a) a traveling paper-carriage; (b) a motor; (c) one or more keys at the key-board acting when depressed to bring said motor into operation; (d) means for printing operated by said motor; (e) means operated by the carriage aforesaid, acting to prevent said motor from printing; and (f) means whereby the point in the travel of the paper-carriage aforesaid at which it prevents the motor aforesaid from printing, is regulated.

105 15. In combination in a type-writing machine, (a) a traveling paper-carriage; (b) an electro-magnet; (c) one or more keys at the key-board serving when depressed to bring said magnet into action; and (d) means operated by the paper-carriage aforesaid, acting to prevent said magnet from operating.

110 16. In combination in a type-writing machine, (a) a traveling paper-carriage; (b) an electro-magnet; (c) one or more keys at the key-board serving when depressed to bring said magnet into action; and (d) a contact device in the circuit of said magnet, normally closing a gap in said circuit; the paper-carriage aforesaid controlling said contact device and acting to open a gap in the circuit of the magnet aforesaid, thereby to prevent said magnet from operating.

115 17. In combination in a type-writing ma-

- chine, (a) a traveling paper-carriage; (b) an electro-magnet; (c) one or more keys at the key-board serving when depressed to bring said magnet into action; (d) means operated by the paper-carriage aforesaid, acting to prevent said magnet from operating; and (e) means whereby the point in the travel of said paper-carriage at which it prevents the magnet aforesaid from operating, is regulated. 10
18. In combination in a type-writing machine, (a) a traveling paper-carriage; (b) an electro-magnet; (c) one or more keys at the key-board, serving when depressed to bring said magnet into action; (d) a contact device in the circuit of said magnet, normally closing a gap in said circuit; the paper-carriage aforesaid controlling said contact device and acting to open a gap in the circuit of the magnet aforesaid, thereby to prevent said magnet from operating; and (e) means whereby the point in the travel of said paper-carriage at which it prevents the magnet aforesaid from operating, is regulated. 15
19. In combination in a type-writing machine, (a) a traveling paper-carriage; (b) an electro-magnet; (c) one or more keys at the key-board, serving when depressed to bring said magnet into action; (d) means for printing, operated by said electro-magnet; and (e) means operated by the paper-carriage aforesaid and acting to prevent said magnet from printing. 20
20. In combination in a type-writing machine, (a) a traveling paper-carriage; (b) an electro-magnet; (c) one or more keys at the key-board, serving when depressed to bring said magnet into action; (d) means for printing, operated by said electro-magnet; and (e) a contact device in the circuit of said magnet, normally closing a gap in said circuit; the paper-carriage aforesaid controlling said contact device and acting to open a gap in the circuit of the magnet aforesaid, thereby to prevent said magnet from printing. 25
21. In combination in a type-writing machine, (a) a traveling paper-carriage; (b) an electro-magnet; (c) one or more keys at the key-board, serving when depressed to bring said magnet into action; (d) means for printing, operated by said electro-magnet; (e) means operated by the paper-carriage aforesaid and acting to prevent said magnet from printing; and (f) means whereby the point in the travel of the paper-carriage at which it prevents the magnet aforesaid from printing, is regulated. 30
22. In combination in a type-writing machine, (a) a traveling paper-carriage; (b) an electro-magnet; (c) one or more keys at the key-board, serving when depressed to bring said magnet into action; (d) means for printing, operated by said electro-magnet; (e) a contact device in the circuit of said magnet, normally closing a gap in said circuit; the paper-carriage aforesaid controlling said contact device and acting to open a gap in the circuit of the magnet aforesaid, thereby to prevent said magnet from printing; and (f) means whereby the point in the travel of the paper-carriage at which it prevents the magnet aforesaid from printing, is regulated. 35
23. In combination in a type-writing machine, (a) a type-bar; (b) a motor serving to actuate said type-bar; (c) a key at the key-board and means controlled by said key whereby, when said key is depressed, the motor aforesaid is brought into action to operate the type-bar; (d) a traveling paper-carriage; and (e) means operated by said paper-carriage and acting to prevent the motor aforesaid from actuating a type-bar. 40
24. In combination in a type-writing machine, (a) a type-bar; (b) a motor serving to actuate said type-bar; (c) a key at the key-board and means controlled by said key whereby, when said key is depressed, the motor aforesaid is brought into action to operate the type-bar; (d) a traveling paper-carriage; (e) means operated by said paper-carriage and acting to prevent the motor aforesaid from actuating a type-bar; and (f) means whereby the point in the travel of the paper-carriage at which it prevents the motor aforesaid from operating a type-bar, is regulated. 45
25. In combination in a type-writing machine, (a) a type-bar; (b) an electro-magnet serving to actuate said type-bar; (c) a key at the key-board for controlling said magnet; (d) a traveling paper-carriage; and (e) means operated by said paper-carriage and acting to prevent the electro-magnet aforesaid from operating. 50
26. In combination in a type-writing machine, (a) a type-bar; (b) an electro-magnet serving to actuate said type-bar; (c) a key at the key-board for controlling said magnet; (d) a traveling paper-carriage; and (e) a contact device in the circuit of the electro-magnet aforesaid, normally closing a gap in said circuit; the paper-carriage aforesaid controlling said contact device and acting to open a gap in the circuit of the magnet aforesaid, thereby to prevent said magnet from actuating a type-bar. 55
27. In combination in a type-writing machine, (a) a type-bar; (b) an electro-magnet serving to actuate said type-bar; (c) a key at the key-board for controlling said magnet; (d) a traveling paper-carriage; (e) means operated by said paper-carriage and acting to prevent the electro-magnet aforesaid from operating; and (f) means whereby the point in the travel of the paper-carriage at which it prevents the electro-magnet aforesaid from operating, is regulated. 60
28. In combination in a type-writing ma- 65

chine, (a) a type-bar; (b) an electro-magnet serving to actuate said type-bar; (c) a key at the key-board for controlling said magnet; (d) a traveling paper-carriage; (e) a contact-device in the circuit of the magnet aforesaid, normally closing a gap in said circuit; the paper carriage aforesaid controlling said contact device and acting to open a gap in the circuit of the magnet aforesaid, thereby to prevent said magnet from actuating the type-bar; and (f) means whereby the point in the travel of the paper-carriage at which it prevents the electro-magnet aforesaid from operating, is regulated.

29. In combination in a type-writing machine, (a) a plurality of type-bars striking to a common printing center; (b) a motor device common to said type-bars for actuating said type-bars, each as required; (c) keys, and means controlled thereby, whereby said motor device is brought into action to operate the different type-bars to which it is common, each type-bar as required; (d) a traveling paper-carriage; and (e) means operated by said paper-carriage and acting to prevent the motor device aforesaid from actuating a type-bar.

30. In combination in a type-writing machine, (a) a plurality of type-bars striking to a common printing center; (b) a motor device common to said type-bars for actuating said type-bars, each as required; (c) keys, and means controlled thereby, whereby said motor device is brought into action to actuate the different type-bars to which it is common, each type-bar as required; (d) a traveling paper-carriage; (e) means operated by said paper-carriage and acting to prevent the motor device aforesaid from actuating a type-bar; and (f) means whereby the point in the travel of the paper carriage at which it prevents the motor device aforesaid from operating a type-bar, is regulated.

31. In combination in a type-writing machine, (a) a plurality of type-bars striking to a common printing center; (b) an electro-magnet common to said type-bars for actuating said type-bars, each as required; (c) keys, and means controlled thereby, whereby said electro-magnet is brought into action to operate the different type-bars to which it is common, each type-bar as required; (d) a traveling paper-carriage; and (e) means operated by said paper-carriage and acting to prevent the electro-magnet aforesaid from operating.

32. In combination in a type-writing machine, (a) a plurality of type-bars striking to a common printing center; (b) an electro-magnet common to said type-bars for actuating said type-bars, each as required; (c) keys, and means controlled thereby, where-

by said electro-magnet is brought into action 65 to operate the different type-bars to which it is common, each type-bar as required; (d) a traveling paper-carriage; and (e) a contact device in the circuit of the electro-magnet aforesaid, normally closing a gap in said 70 circuit; the paper-carriage aforesaid controlling said contact device and acting to open a gap in the circuit of the electro-magnet aforesaid, thereby to prevent said electro-magnet from actuating a type-bar. 75

33. In combination in a type-writing machine, (a) a plurality of type-bars striking to a common printing center; (b) an electro-magnet common to said type-bars for actuating said type-bars, each as required; (c) 80 keys, and means controlled thereby, whereby said electro-magnet is brought into action to operate the different type-bars to which it is common, each type-bar as required; (d) a traveling paper-carriage; (e) means operated by said paper-carriage and acting to prevent the electro-magnet aforesaid from 85 operating; and (f) means whereby the point in the travel of the paper-carriage at which it prevents the electro-magnet aforesaid 90 from operating, is regulated.

34. In combination in a type-writing machine, (a) a plurality of type-bars striking to a common printing center; (b) an electro-magnet common to said type-bars for actuating said type-bars, each as required; (c) 95 keys, and means controlled thereby, whereby said electro-magnet is brought into action to operate the different type-bars to which it is common, each type-bar as required; (d) a traveling paper-carriage; (e) a contact device in the circuit of the electro-magnet aforesaid, normally closing a gap in said 100 circuit; the paper-carriage aforesaid controlling said contact device and acting to open a gap in the circuit of the electro-magnet aforesaid, thereby to prevent said magnet from actuating a type-bar; and (f) means whereby the point in the travel of the paper-carriage at which it prevents the electro-magnet aforesaid 105 from operating, is regulated.

35. In combination, in a typewriting machine (a) a motor; (b) a motor controlling device therefor; (c) a traveling paper carriage; and (d) adjustable connections between the carriage aforesaid and the motor controlling device aforesaid; said connections being operated by the normal movement of the carriage aforesaid and serving 110 when thus operated to prevent the motor aforesaid from operating; whereby the point in the normal movement of the paper carriage at which it prevents the motor aforesaid from operating may be altered as required. 115

36. In combination, in a typewriting machine (a) a motor; (b) a motor controlling

device therefor; (c) a rack connected with said motor controlling device; (d) a member adjustable on said rack; and (e) a member traveling with the paper carriage and acting during the normal movement of said paper carriage on the member last mentioned to give movement to the rack aforesaid, thereby to operate the motor controlling device aforesaid in such a manner that said motor controlling device prevents the motor aforesaid from operating.

37. In combination, in a typewriting machine (a) an electromagnet; (b) a circuit breaking device therefor; (c) a traveling paper carriage, and (d) adjustable connections between said carriage and said circuit breaking device, operated by the normal movement of said carriage and acting to prevent the electromagnet aforesaid from operating; whereby the point in the normal movement of the paper carriage aforesaid at which said carriage operates to prevent the electromagnet aforesaid from operating may be regulated.

38. In combination, in a typewriting machine (a) an electromagnet; (b) a circuit breaking device therefor; (c) a rack connected with said circuit breaking device; (d) a member adjustable on said rack; and (e) a member traveling with the paper carriage and acting during the normal movement of said carriage on the member last mentioned to give movement to the rack aforesaid; thereby to operate the circuit controlling device aforesaid in such manner that it prevents the electromagnet aforesaid from operating.

39. In combination, in a typewriting machine, (a) a motor for printing; (b) a motor-controlling device therefor; (c) a traveling paper-carriage; and (d) adjustable connections whereby the motor aforesaid is made to act upon the motor-controlling device aforesaid at the required point in said carriage's travel, in such manner as to prevent the motor aforesaid from printing.

40. In combination, in a typewriting machine, (a) a motor for printing; (b) a motor-controlling device therefor; (c) a rack connected with said motor-controlling device; (d) a member adjustable on said rack; and (e) a member traveling with the paper-carriage and acting on the member last mentioned to give movement to the rack aforesaid, thereby to operate the motor-controlling device aforesaid, in such manner as to prevent the motor aforesaid from printing.

41. In combination, in a typewriting machine, (a) an electromagnet for printing; (b) a circuit-controlling device for said electromagnet; (c) a traveling paper-carriage; and (d) adjustable connections whereby the carriage aforesaid is made to act upon the circuit-controlling device aforesaid at the required point in said carriage's travel.

42. In combination, in a typewriting machine, (a) an electromagnet for printing; (b) a circuit-controlling device for said electromagnet; (c) a rack for operating said circuit-controlling device; (d) a member, adjustable on said rack; and (e) a member, traveling with the paper-carriage and acting on the member last mentioned to give movement to the rack aforesaid, thereby to operate the circuit-controlling device aforesaid. 70 75

43. In combination, in a typewriting machine (a) mechanism for printing; (b) a motor for operating said printing mechanism; (c) a traveling paper carriage; and (d) means operated by said traveling paper carriage whereby the motor aforesaid is prevented from operating the printing mechanism aforesaid. 80

44. In combination, in a typewriting machine (a) mechanism for printing; (b) an electromagnet for operating said printing mechanism; (c) a traveling paper carriage; and (d) means operated by said traveling paper carriage whereby the electromagnet aforesaid is prevented from operating the printing mechanism aforesaid. 85 90

45. In combination, in a typewriting machine (a) mechanism for printing; (b) motor mechanism for operating said printing mechanism; (c) a traveling paper carriage; and (d) adjustable connections whereby the carriage aforesaid is made, at the required point in the travel of said paper carriage, to prevent the motor mechanism aforesaid from operating the printing mechanism 100 aforesaid. 95

46. In combination, in a typewriting machine (a) mechanism for printing; (b) an electromagnet for operating said printing mechanism; (c) a traveling paper carriage; and (d) adjustable connections whereby the carriage aforesaid is made, at the required point in its travel, to prevent the electromagnet aforesaid from operating the printing mechanism aforesaid. 105 110

47. In combination in a typewriting machine (a) means for printing; (b) a motor for operating said printing means; (c) a controlling device for said motor; (d) a traveling paper carriage; and (e) adjustable connections whereby said carriage is made to act, at the required point in its travel, upon the motor-controlling device aforesaid, to prevent said motor from operating the printing means aforesaid. 115 120

48. In combination, in a typewriting machine (a) means for printing; (b) a motor for operating said printing means; (c) a controlling device for said motor; (d) a rack connected with said motor controlling device; (e) a member adjustable on said rack; and (f) a member traveling with the paper carriage and acting on the member last mentioned to give movement to the rack aforesaid, thereby to operate the motor con- 125 130

- trolling device aforesaid in such manner as to prevent the motor aforesaid from printing.
49. In combination, in a typewriting machine (a) means for printing; (b) an electromagnet for operating said printing means; (c) a circuit controlling device for said electromagnet; (d) a traveling paper carriage; and (e) adjustable connections whereby the carriage aforesaid is made to act upon the circuit controlling device aforesaid at the required point in such carriage's travel.
50. In combination, in a typewriting machine, (a) means for printing; (b) an electro-magnet for operating said printing means; (c) a circuit-controlling device for said electro-magnet; (d) a traveling paper carriage; and (e) adjustable connections, whereby the carriage aforesaid is made to act upon the circuit-controlling device aforesaid, at the required point in such carriage's travel; said circuit-controlling device operating, when thus acted on by the traveling paper carriage, to prevent the electro-magnet before mentioned from operating the printing mechanism.
51. The combination in an electrically-operated typewriting machine including electrically-operated devices for actuating the type bars arranged in a normally open circuit, of means for closing the circuit to cause a type bar to be actuated, a normally closed circuit breaker arranged in said normally open circuit, and means operated by the movement of the carriage for causing said normally closed circuit breaker to break the circuit.
52. The combination in an electrically-operated typewriter including an electrically-operated device for actuating the type bars arranged in a normally open circuit, of means for closing the circuit to cause a type bar to be actuated, and means operated by the movement of the carriage to so break the circuit that the type bars cannot be actuated.
53. The combination with an electrically-operated typewriter including an electrically-operated device for actuating the type bars and an electrical circuit including said device and "make and break" mechanism located in said circuit, of a longitudinally movable gage bar supported independently of the carriage, means interposed between the same and the carriage for shifting said bar and means interposed between said bar and said "make and break" mechanism for actuating the latter.
54. The combination with an electrically-operated typewriting machine including an electrically-operated device for actuating the type bars, an electrical circuit including said device and "make and break" mechanism located in said circuit; of a longitudinally shiftable gage bar supported independently of the carriage, a stop carried by said bar, a device projecting from the carriage of the machine co-acting with said stop, and means interposed between said bar and the "make and break" mechanism actuated by the former in the longitudinally shifting movement for operating said "make and break" mechanism.
55. In combination, in an automatic printing-preventing action for a power-operated typewriting machine, in which the printing-preventing mechanism operates by cutting off power from the motor mechanism, a longitudinally-movable gage-bar and connections operated by said bar for cutting off the power from the printing mechanism.
56. In a typewriting machine, in which the type-bars are operated by a motor device, the combination, with said type-bars and motor device, of a gage-bar, controlling said motor device, with an adjustable stop for moving longitudinally upon said gage-bar.
57. In an electrical typewriting machine, in which the type-bars are actuated by the force of the so-called electrical current, the combination, with the type-bar operating electro-magnet, of a gage-bar, controlling said electro-magnet, and an adjustable stop for moving longitudinally upon said gage-bar.
58. In a typewriting machine, having means for printing, and a motor for operating said printing means, the combination with said motor of a motor-controlling gage-bar, and an adjustable stop for moving longitudinally on said gage-bar.
59. In a typewriting machine, having means for printing, and a motor for operating said printing means, the combination with said printing means of an electrically-operated motor, for actuating said printing means, and the combination with said motor of a circuit-controlling gage-bar, acting upon a circuit of the motor mechanism aforesaid, so as to control the action of said motor, and an adjustable stop for moving longitudinally on said gage-bar.
60. In a power-operated typewriting machine, the combination with a motor-controlling gage-bar as 52, of a stop adjustable longitudinally on said gage-bar, said stop serving when engaged by the carriage to move the gage-bar from its normal position; and means whereby the carriage is permitted to move on toward the left a further distance, even after it has engaged such gage-bar.
61. In a type-writing machine, in which the printing is effected by an electrically controlled device, means for preventing the type from printing as the end of the line is approached, which consists in interrupting a circuit of the electrically operated device

aforesaid, when the carriage reaches the position required.

62. In a type-writing machine in which the printing is effected by the action of an electro-magnet, means for preventing the type from printing at the end of a line, which consists in breaking the circuit of the printing electro-magnet aforesaid, by the movement of the paper carriage.

10 In testimony whereof I have hereunto set

my hand at Washington, in the District of Columbia, this twelfth day of October, A. D. nineteen hundred, in the presence of the subscribing witnesses, whose names are here-to affixed.

THADDEUS CAHILL.

Witnesses:

HENRY E. COOPER,
MARTIN J. McCIKE.
